UNITED STATES PATENT OFFICE

ABRAHAM BLUSTEIN, OF HAVERHILL, MASSACHUSETTS, ASSIGNOR, BY MESNE ASSIGNMENTS, TO THE BROWN COUNTER COMPANY, OF HAVERHILL, MASSACHUSETTS, A COPARTNERSHIP CONSISTING OF HARRY BROWN AND ABRAHAM BLUSTEIN

COUNTER-ROLLING MACHINE

Application filed November 11, 1929. Serial No. 406,309.

This invention relates to an improved counter rolling machine which is particularly adapted to receive a flat counter blank and to impart a convex curvature to the same. Counters are commonly formed of sheets of thin fiber board, i. e. a vegetable pulp product which has been treated with a suitable sizing or impregnating agent, this fiber board being cut to form separate blanks, then skived and shaped to provide it with the proper form. During the initial shaping or rolling operation wax or the like is commonly applied to the fiber board counter as it is inserted between a ball-shaped forming roll and a concave die or cup, these members being disposed and arranged to impart pressure to the inserted blank so that the sizing or indurating agent becomes substantially solidified. Heretofore these machines have been arranged to impart uniform pressure to substantially the entire area of the blank so that the whole blank was thus stiffened.

In accordance with the improved method of manufacturing counters disclosed in my copending application Serial No. 387,418, filed August 21, 1929, the stiffening treatment is confined to that portion of the counter blank which forms the lower part of the ultimate counter, thus leaving the upper part of the counter relatively flexible or non-stiffened. Such counters are particularly advantageous in the manufacture of shoes since they possess the desirable characteristics of the higher-priced leather counters and permit the proper shaping or forming of the shoes under the commercial processes ordinarily employed and since they permit the finished shoe to have a flexibility and conformability to the shape of the foot which was heretofore permitted only by leather counters and thus avoid undesirable chafing or blistering of the wearer's foot.

The present invention provides a counter rolling machine which is adapted to permit the manufacture of counters of this character by confining the application of pressure to one portion of the counter blank while affording a suitable guiding and retaining means for all portions of the blank

as it passes between the cup or die and the roller. Furthermore in the preferred embodiment of the invention the parts are so arranged that there is no sharp demarcation between the stiffened area and the relatively flexible non-stiffened area that ultimately is to form the upper margin of the counter. To permit this desirable result I preferably provide the cup with a concavity adjoining one side with its surface depressed below the adjoining surface that presses the blank against the rotatable ball or roller. Preferably the depressed surface of the concavity of the cup gradually merges into the pressure-receiving portion thereof that has a surface curved to be substantially complementary to that of the roller and preferably the edges of the depressed surface of the cup merge with continuations of the pressure-receiving surface of the same thereby affording suitable guide means for the blank as it passes between the ball and cup.

An arrangement of this character is effective in substantially confining the application of pressure and consequent stiffening of the blank to one portion of the same, while avoiding a sharp line of demarcation between the stiffened and non-stiffened portions and while permitting the convenient insertion and passage of the blank between the roller and cup without objectionable tendency of the same to turn or twist. Accordingly a machine of the character afforded by the present invention may be operated with the same facility as the machines heretofore provided, while permitting the more advantageous results which are attainable by the improved process of manufacturing counters disclosed in my above-identified copending application.

In the accompanying drawings:

Fig. 1 is a sectional view of a typical cup and roller and related parts employed in a machine of the general character to which my invention is applicable;

Fig. 2 is a section taken axially of the roller showing a portion of the latter and the improved form of cup;

Fig. 3 is a section indicated by the line 3—3 of Fig. 2; and

Fig. 4 is a perspective view of a counter which has passed through my improved machine, the stippling indicating the stiffened portion of the counter.

My invention is generally applicable to the class of counter rolling machines in common use in this art and the general construction of which is well known to those familiar with the art; for example, for an understanding of the same reference may be had to the patent to Stewart No. 637,533, issued November 21, 1899. Since the present invention concerns only the construction and arrangement of the cup and roll, the present disclosure is substantially confined to the improved parts of the machine.

Referring to the accompanying drawings, the numeral 1 designates a unitary cup which may be urged by a spring 2 toward a complementarily formed ball-like roller 3 which rotates upon a suitable axial member 14. The guide bars 19 engage the ends of the cup and hold the same against lateral twisting, while the stops 10 limit its movement under the action of the spring 2. In accordance with this invention one side of the cup 1 may have a surface which is formed to be substantially complementary to the convex surface of the adjoining ball 3; this portion of the cup being designated by the numeral 4 and being similar to that ordinarily employed in machines of this character. The other side of the cup preferably is provided with a depression 5 which provides an appreciable cavity between the surface of the cup and the adjoining surface of the roll. Preferably the depressed surface 5 of the cup gradually merges into the surface 4, as designated by numeral 6.

Fig. 3 shows the preferred shape of the cavity or depression 5 which has its maximum depth adjoining the central part of the cup which merges into surfaces 9 which are substantial continuations of the surfaces of the pressure-receiving portion 4 of the cup at its upper and lower edges. These surfaces 9 are effective in engaging the counter as it enters and leaves the space between the cup and roll and in serving as guide means for the same, and thus affording a light frictional engagement with the blank which aids its proper insertion and movement through the machine. It is, of course, understood that the maximum pressure is imparted to the counter blank in a region adjoining the center of the cup as viewed for example in Fig. 1 and that in accordance with this invention the concavity 5 preferably has its maximum depth in this region.

In the operation of a machine of this character one end of the blank is inserted

between an edge of the cup and the roll in the conventional manner and the rotation of the roll results in the movement of the blank between the roll and cup, the spring 2 being effective to impart considerable pressure to that portion of the blank which passes between the surface 4 and the ball 3 while this pressure becomes gradually less adjoining the portion 6 of the cup and is substantially absent in the region of the concavity 5. Thus the entire pressure received from the spring 2 may be substantially confined to one portion of the counter, thus imparting an unusually effective stiffening action upon this portion of the counter and leaving the remainder of the same substantially flexible.

Fig. 4 illustrates the counter blank in the form in which it leaves a machine of this character, the stippled area designated by numeral 11 being stiffened or hardened by the pressure imparted thereto and the remainder of the counter remaining substantially free from the stiffening action.

It is thus evident that this invention provides an improved counter rolling machine which permits the application of highly effective stiffening pressure to one portion of the counter while avoiding the application of this pressure to that part of the counter where such treatment is undesirable.

I claim:

1. In a machine of the class described, a roller, a cup juxtaposed thereto and having a pressure-receiving surface shaped to conform to the curvature of the adjoining roller, said cup having one side provided with a concavity with its surface depressed below that of the pressure-receiving surface.

2. In a machine of the class described, a roller, a cup juxtaposed thereto and having a pressure-receiving surface shaped to conform to the curvature of the adjoining roller, said cup having one side provided with a concavity with its surface depressed below that of the pressure-receiving surface, the latter gradually merging into the concavity.

3. In a machine of the class described, a roller, a cup juxtaposed thereto and having a pressure-receiving surface shaped to conform to the curvature of the adjoining roller, said cup having one side provided with a concavity having its surface depressed below that of the pressure-receiving surface, the surface of the concavity gradually merging into a continuation of the pressure-receiving surface at an edge of the cup.

4. In a machine of the class described, a roller, a cup juxtaposed thereto and having a pressure-receiving surface shaped to conform to the curvature of the adjoining roller, said cup having one side provided with a concavity having its surface depressed below that of the pressure-receiving sur-

face, the pressure-receiving surface gradually merging into the surface of the concavity, and the surface of the concavity gradually merging into a continuation of the pressure-receiving surface at an edge of the cup.

5. In a machine of the class described, a cup member, a roller member, said members being disposed in juxtaposition, one of said members having a pressure-receiving area formed with a curvature substantially complementary to that of the other member, and another surface depressed below said region and arranged to prevent the application of pressure to the adjoining portion of
10 a blank passing between the cup and roller, whereby the application of pressure to the blank is confined to the pressure-receiving region.

Signed by me at Boston, Massachusetts,
20 this ninth day of November, 1929.

ABRAHAM BLUSTEIN.
